PACKAGE LINER

Harry E. Engleson, Chicago, and Elmer D. Sramek, Cicero, Ill., assignors to F. B. Redington Co., Chicago, Ill., a corporation of Delaware

Filed Aug. 30, 1956, Ser. No. 607,131

4 Claims. (Cl. 229—14)

This invention relates to a package and method of making same, and more particularly to a package in the form of a liner adapted to be received within a cardboard container or the like, wherein the liner is constructed of a flexible laminated material in the form of a tubular sleeve having the opposite end portions closed, thereby defining a moistureproof and an hermetic liner.

The present invention is particularly useful in connection with the packaging of candied popcorn and the like, and other perishable commodities which may be kept fresh in an airtight and moistureproof package.

In the present invention, a tubular sleeve, rectangular in cross section, is formed from a sheet of laminated material having an aluminum foil ply and a waxen paper ply bonded together. This material is known as "Reyseal." The tubular sleeve is provided with a longitudinal heat-sealed seam along one of the broad faces and folded over at the opposite ends so that the waxen ply contacts another portion of the waxen ply or the waxen ply contacts the foil ply. Application of heat to the folded end portions closes the ends in a moistureproof and airtight relationship.

Accordingly, it is an object of this invention to provide an improved package and method of making same which is airtight and moistureproof.

Another object of this invention is in the provision of a package for containing perishable commodities that is constructed of a laminated material having a foil ply and a waxen paper ply, wherein the ends of the package are folded in such a manner that the waxen ply either contacts another portion of the waxen ply or a portion of the foil ply to define a moistureproof and airtight sealed package.

Still another object of this invention resides in the provision of a liner adapted to be received in a cardboard container having moistureproof and airtight closures at each end thereof which may be simply and readily constructed at low cost.

Other objects, features, and advantages of the invention will be apparent from the following detailed disclosure, taken in conjunction with the accompanying sheets of drawings, wherein like reference numerals refer to like parts, in which:

Fig. 1 is a perspective view having some portions broken away of a tubular sleeve which illustrates the first step in forming this invention;

Fig. 2 is a fragmentary view of the bottom end of the sleeve in Fig. 1 illustrating the next step of folding inwardly an end flap;

Fig. 3 is a fragmentary view similar to Fig. 2, but illustrating the next step performed in fashioning the end enclosure of the liner of the instant invention; and

Fig. 4 is a fragmentary perspective view of the completed end closure of the liner of the instant invention.

Referring to the drawing and particularly to Fig. 1, a tubular sleeve 10 of rectangular cross section is illustrated which comprises broad sides 11, 11 and narrow sides 12, 12. This tubular sleeve is constructed from a sheet of

2

laminated material, known as "Reyseal" which includes an aluminum foil ply 13 bonded to a waxen paper ply 14 for defining a composite sheet. "Reyseal" is characteristic in that upon application of heat, the paper ply will seal on the foil ply or the paper ply will seal on the paper ply, but the foil ply will not seal on the foil ply. And, it may be formed in the conventional manner, wherein opposite ends 15 and 16 are brought into overlapping relationship along one of these broad sides. It will be noted that the tubular sleeve is formed so that the waxen ply 14 is innermost with the foil ply 13 being on the outside.

In overlapping the ends 15 and 16, it is seen that the foil ply of the end 16 is in engagement with the waxen paper ply of the end 16. Heat is applied along these overlapping ends in order to seal them together and define a longitudinally extending seam 17.

In closing the open end, panels 21, 22 are folded inwardly along the line 23 until they are positioned normal to the broad side 11, as shown in Fig. 2. In making this fold, a portion of the side extensions 18 and 20 are folded upon themselves so that diagonal creases 24 and 25 are formed. Thus, a portion of the innermost paper ply of each side extension is folded over into engagement with another portion thereof. The front extension 19 is then folded inwardly in overlapping relationship with respect to the panels 21, 22 until the extension is normal to the broad side 11, as seen in Fig. 3. This operation also causes a portion of the side extensions 18 and 19 to be folded inwardly and in overlapping position with other portions of these side extensions, wherein diagonal creases 26 and 27 are defined. Now, triangularly shaped sections or tabs 28 and 29 are defined by the folding operation.

In folding the front extension 19 over panels 21, 22, the innermost waxen paper ply 14 of the extension contacts the outermost foil plies of the panels 21, 22 defining paper to foil contact. With respect to the side extensions, a portion of the inner waxen ply of the extensions will contact a portion of the inner waxen ply of other portions of the extensions and the outer foil ply of the already folded over portions of these extensions. Thereafter, heat is applied to the folded portions in order to adhesively seal all of the folds together and define a moistureproof and hermetic end closure. Thus, it is seen that the entire package is completely sealed along the longitudinal seam and at each end thereof with portions of the waxen ply contacting the foil ply or the portions of the waxen ply. The triangular projections or tabs 28 and 29 may then be folded inwardly against the overlapping folded extensions, as shown in Fig. 4, to define a completely sealed end closure. A thermoplastic or a hot melt adhesive may be applied to the inner faces of the triangular tabs 28 and 29 in order to secure them in position against the overlapping extension.

From the foregoing, it will be appreciated that the present invention provides a liner of laminated material including an aluminum foil ply and a waxen paper ply which is folded in such a manner so that the entire package is completely sealed with paper against foil or paper against paper in order to provide a moistureproof and hermetic liner.

It will be understood that modifications and variations may be effected without departing from the scope of the novel concepts of the present invention, but it is understood that this application is to be limited only by the scope of the appended claims.

The invention is hereby claimed as follows:

1. A relatively flexible walled liner adapted to be received in a container constructed of stiffer material, said liner being formed from a composite sheet of laminated material having an outer ply of aluminum foil and an

inner ply of waxen paper bonded to said foil, said liner comprising an elongated rectangular in cross section tubular member having opposing broad and narrow side portions and a folded and sealed closure at each end thereof, each closure including an inner flap connected to one of said broadside portions, an outer flap connected to said other broad side portion and in overlapping sealed relationship to said inner flap so that the paper ply of said outer flap contacts the foil ply of said inner flap in hermetic and moistureproof relationship, and multi-layer triangular tabs connected to said opposite narrow side portions and overlapping said inner and outer flaps, said multi-layer tabs including paper plies directly contacting and bonded to paper and foil plies.

2. A method of making a container which comprises providing a composite sheet of laminated material having an outer ply of aluminum foil and an inner ply of waxen paper bonded thereto, folding said sheet in the form of an elongated tube rectangular in cross section with the paper ply facing innermost thereby defining two broad sides and two narrow sides, bringing the longitudinally extending free marginal edges of said material in face-to-face relationship with the paper ply overlapping and contacting the foil ply, applying heat to said marginal edges to provide a longitudinal seam for said tube which is hermetically sealed, folding the marginal edge of one of said broad sides at each end of said tube inwardly at right angles to said broad side causing adjacent connected portions of said narrow sides to fold over part of the remote portions thereof to place the paper plies of said portions in face-to-face contact, folding the marginal edge of said other broad side at each end of said tube inwardly at right angles to said broad sides in overlapping position to said first inwardly folded edge so that the paper ply of the former contacts the foil ply of the latter, and causing the adjacent connected portions of said narrow sides to fold over the remote portions thereof and the already folded portions to place the paper plies of said connected portions in contact with the paper ply of said remote portions and the foil ply of said already folded portions wherein triangular tabs are formed, applying heat to said folded end portions to bond the paper against paper plies and the paper against foil plies and define moistureproof and hermetically sealed folded end portions, and folding over the triangular tabs against the folded broad sides.

3. A relatively flexible walled liner adapted to be received in a container constructed of stiffer material, said liner being formed from a composite sheet of laminated material having an outer ply of aluminum foil and an inner ply of waxen paper bonded to said foil, said liner comprising an elongated rectangular in cross section tubular member having opposed side portions and a folded and sealed closure at each end thereof, each closure in-

cluding an inner flap connected to one of said side portions and an outer flap connected to the side portion opposed thereto and in overlapping sealed relationship to said inner flap so that the paper ply of said outer flap contacts the foil ply of said inner flap in hermetic and moistureproof relationship, and multi-layer substantially triangular-shaped tabs connected to other opposite side portions and overlapping said inner and outer flaps, said multi-layer tabs including paper plies directly contacting and bonded to paper and foil plies.

4. A method of making a container which comprises providing a composite sheet of laminated material having an outer ply of aluminum foil and an inner ply of waxen paper bonded thereto, folding said sheet in the form of an elongated tube rectangular in cross section with the paper ply facing innermost thereby defining two pairs of opposed sides, bringing the longitudinally extending free marginal edges of said material in face-to-face relationship with the paper ply overlapping and contacting the foil ply, applying heat to said marginal edges to provide a longitudinal seam for said tube which is hermetically sealed, folding the marginal edge of one of the sides of one pair of opposed sides at each end of the tube inwardly at right angles to said side causing adjacent connected portions of said other pair of sides to fold over part of the remote portions thereof to place the paper plies of said portions in face-to-face contact, folding the marginal edge of said other of the sides of said one pair of opposed sides at each end of the tube inwardly at right angles to said side in overlapping position to said first inwardly folded edge so that the paper ply of the former contacts the foil ply of the latter, and causing the adjacent connected portions of said other pair of sides to fold over the remote portions thereof and the already folded portions to place the paper plies of said connected portions in contact with the paper ply of said remote portions and the foil ply of said already folded portions wherein substantially triangularly-shaped tabs are formed, applying heat to said folded end portions to bond the paper against paper plies and the paper against foil plies and define moistureproof and hermetically sealed folded end portions, and folding over the tabs against the folded said one pair of sides.
